UNITED STATES PATENT OFFICE

CHARLES WILLIAM LAND, OF BRIGHTON, VICTORIA, AUSTRALIA

VISIBLE-INDEX-CARD FILING DEVICE

Application filed June 26, 1928, Serial No. 288,406, and in Australia July 5, 1927.

This invention relates to visible index card filing devices embodying card holders which are adapted to be hingedly retained in drawers or trays and normally to lie in upwardly and forwardly overlapped formation so that indicia of the cards are visible when the drawer is opened, the hingeable retaining means permitting the holders to be swung upwardly and rearwardly when so desired.

In existing devices of the kind indicated the cards are retained directly to the holders usually by having their upper corner portions inserted into diagonal slits formed in the holder, and their lower edge portions entered into folded or U shaped strips of celluloid or like transparent material which are secured to the lower edges of the holders.

A disadvantage of such existing devices is the inconvenience of inserting and removing the cards, especially if corners of the cards require to be inserted in and removed from diagonal slits in the holder. Furthermore, repeated insertion and removal of the cards is likely to cause their corners to become creased or "dog-eared."

Another objection which is experienced in existing devices wherein the transparent strip at the lower edge of a card is utilized to accommodate signal tabs, is that, in the event of a card being removed from its holder, as is frequently necessary, for instance when the card is to be inserted in a typewriting or a tabulating machine, the signal tab is likely to be inadvertently displaced either entirely from its holder or from the correct transverse position thereon.

The present invention aims to overcome the above objections by facilitating the insertion and removal of cards, and generally to increase the efficiency of such devices. To this end I provide for each holder, hereinafter referred to as a main or rear holder, a supplemental holder, and a retaining element for retaining said supplemental holder to the main holder and for retaining a card or cards to said supplemental holder, the arrangement being such that cards may be speedily and easily inserted into and removed from said supplemental holder without damage or wear to the cards and without displac-

ing any signal tabs which may be used in conjunction with the main holder.

Referring to the drawings which form part of this specification:—

Figure 1 is a front view of a supplemental card holder in accordance with a preferred embodiment of the invention, applied to a main holder.

Figure 2 is a vertical section, on an enlarged scale, of the parts shown in Figure 1, the thicknesses of the parts being exaggerated for convenience of illustration.

Figure 3 is a front view of a supplemental card holder, according to a modification, applied to a main holder.

Figure 4 is a front view of a supplemental card holder according to another modification.

Figures 5 and 6 are front views of a main holder and a supplemental holder according to other modifications of the invention.

In accordance with this invention I employ a supplemental card holder 2 which is provided at its bottom with an upturned index portion 3 which is folded upwardly in front of the supplemental holder so as to accommodate the lower edge portion of a card 4. On the front face of this upturned portion 3 of the supplemental holder the name of the person or firm to which the particular card relates, or any other desired indicia, may be inscribed so that it is visible through the front of a transparent folded strip 6 at the lower edge of a main holder 7. The strip 6 provides a pocket in which the lower portion of the supplemental card holder 2 is detachably accommodated.

The main holders 7 may be of any known or suitable form and may have secured thereto a flap 5 provided with sidewise projecting ears 5^a adapted to enter grooves extending longitudinally within the side walls of a drawer according to known practice. The main holder may be creased adjacent its upper edge, as indicated by broken lines 5^b in Figures 1, 3, 5 and 6, so as to form a hinge about which the holder may be swung in relation to its retaining flap 5.

The upper corners of the supplemental holder 2 may be inserted within the usual

diagonal slits 7^a of the main or rear holder 7, as seen in Figures 1, 3 and 6, which slits usually accommodate the upper corners of the cards.

According to a preferred embodiment of the invention, the top portion of a card 4 and also the top intermediate portion of a supplemental holder 2 are removably held in position by a retainer which, as seen in Figure 1, is in the form of a button or tab 9 of celluloid or like transparent material which may be fastened by staples 11 to the upper part of the front of the main holder 7. The retainer 9 is adapted to overlap the adjacent portions of the card 4 and the supplemental holder 2, as seen in Figures 1 and 2, to thereby securely but removably retain such members flat and in proper position on the main holder 7. An open mouthed slot 12 is preferably provided in the supplemental holder 2 adjacent the retainer 9 to enable the top edge of the holder 2 to extend upwardly beyond the staples 11.

If desired, however, a separate retainer 9^a, of celluloid or the like, may be fastened by staples 11^a to the supplemental holder 2', and a slit 14 provided in the main holder 7 to accommodate the tongue formed by an upper end of said retainer, the lower edge being utilized to retain the card 4 as seen in Figure 3. Or if desired, the locations of the retainer 9^a and the slit 14 in relation to the supplemental holder 2 and the main holder 7 may be reversed.

Alternatively, the upper corners of the card 4 projecting above the upper edge of a supplemental holder 2 may be retained within the diagonal slits 7^a of the main or rear holder 7 in the usual manner, in which case, additional diagonal slits (not shown) may be formed in lower positions on the main holder 7 in order to receive the upper corners of the reduced supplemental card holder.

In a further embodiment of the invention as seen in Figure 4, the top of the card 4 may be retained in position by one or more integral tongues 16 cut from the upper part of the supplemental holder 2" and adapted to overlap the upper part of the card.

According to another modification illustrated in Figure 5, the retainer may take the form of an elongated strip 9^b of celluloid or other suitable material which may be stapled as at 11^b to the upper portion of the main holder 7 beneath the hinging crease or fold 5^b thereof. A supplemental holder 2"" is retained to the main holder 7 by the upper edge portion of the holder 2"" being inserted between said strip 9^b and the holder 7. The upper edge portion of a card 4 may also be entered between the strip 9^b and the holder 7 if desired, but the card may be retained in position by being overlapped by a nose or projecting portion 9^c of said strip, this nose 9^c facilitating the application of the supplemental

holder to the main holder, and the card 4 to the supplemental holder.

According to a further modification, an elongated strip 9^d of celluloid or other suitable material may be stapled as at 11^d (Figure 6) to the upper edge of a supplementary holder 2""'. In this instance, the upper corners of the holder 2""' may be inserted in the usual diagonal slits 7^a in the main or rear holder 7 and the strip 9^d may have two noses or portions, one projecting upwardly, 9^e and the other downwardly, 9^f. The upwardly projecting nose 9^e is inserted in a slit 7^b in the rear holder 7, whilst the downwardly projecting nose 9^f facilitates the insertion of a card 4 into the supplemental holder 2""'.

With any of the foregoing arrangements a colored or other suitable signal tab 17, shown in Figure 3, may be readily fitted in the desired position between the front of the upturned portion 3 of the supplemental card holder 2 and the transparent strip 6 at the lower edge of the rear holder 7, so that the tab 17 does not come into contact with the card. The result is that the signal tab is securely but removably held in place and is in no way affected by the removal and replacement of the card. The liability of inadvertently displacing the signal tab, as previously mentioned, is thus overcome in a simple and effective manner.

Where the holders 7 are provided with corner pockets, it will be evident that the corner portions of the supplemental holders 2 etc. may be inserted therein, and suitable signal tabs may be placed over the upturned index-bearing portions 3 of the supplemental holders.

The aforesaid upturned lower portion 3 of each supplemental card holder 2 etc. may be provided with an aperture 18 (as in Figure 4) immediately behind which the face of the holder 2 may be colored or otherwise treated as at 19 in order to render it prominently visible. This colored or like portion is normally obscured by the card 4 which shows through said aperture 18 when the card is in position. When, however, the card is removed from the supplemental holder, the colored or like portion 19 of the latter is seen through the aperture and forms a distinctly visible indication that the card is missing from the holder.

In order to provide a visible index for the cards when the main holders 7 are swung upwardly and rearwardly within a drawer, each main holder may be shaped or cut away adjacent its lower edge to thereby leave a recess 7^e (Figures 1 and 2) which extends practically for the entire width of the holder. At the ends of this recess the holder may have nose portions 8 through which staples 10 or the like are passed for fastening the transparent strip 6 to the holder. The presence of this recess 7^e enables the strip to be made a very close fit upon the corner portions of the hold-

er without impeding insertion and withdrawal of the supplemental holder 2. It will also be evident that the back face of the lower folded portion 3 of a supplemental holder 5 may be readily viewed through said gap 7^c and the transparent strip 6 when the holder 7 is swung rearwardly.

Having now described my invention what I claim as new and desire to secure by Letters Patent is:—

10 1. In a visible index card-filing device, the combination of a main holder adapted for retention within a filing drawer and provided at its lower edge with a pocket, a supplemental card holder adapted at its lower edge to be entered into said pocket of the main holder, and means for detachably retaining said supplemental holder at its upper edge to said main holder and for detachably retaining a 15 card at its upper edge to said supplemental holder.

20 2. In a visible index card-filing device, the combination of a main holder adapted for retention within a filing drawer and provided at its lower edge with a substantially U-shaped transparent strip, a supplemental card holder having a lower edge index-bearing portion adapted to be inserted within said U-shaped strip, and a retainer adapted to retain said supplemental holder at its upper edge to said main holder and to overlap and retain a card at its upper edge to said supplemental holder.

25 3. In a visible index card-filing device, the combination of a main holder adapted for retention within a filing drawer and provided at its lower edge with a transversely extending strip of transparent material forming a pocket, a supplemental card holder having 30 at its lower edge a turned-back portion and adapted to be inserted within said pocket, said turned-back portion serving to accommodate the lower edge portion of a card, and means for detachably retaining said supplemental holder and said card to said main 35 holder.

40 4. In a visible index card-filing device, the combination of main holder adapted for retention within a filing drawer and provided at its lower edge with a pocket, a supplemental card holder provided at its lower edge with a turned-back portion and adapted to be inserted within said pocket, said turned-back portion serving to accommodate the 45 lower edge portion of a card, and a retainer cooperating with the upper edge of said supplemental holder for retaining the latter to said main holder and for overlapping and holding the upper edge of a card in said supplemental holder.

45 5. In a visible index card filing device, the combination of a main holder adapted for retention in a filing drawer, a transparent pocket at the lower edge of said holder, a supplemental card holder having its lower

edge portion turned back upon itself and adapted for insertion within said pocket, and a retainer secured to said main holder and adapted to overlap the upper edges of said supplemental holder and a card thereon. 70

6. In a visible index card filing device, the combination of a main holder adapted for retention in a filing drawer, a transparent strip secured to the lower edge of said holder so as to provide a pocket, a supplemental card holder provided at its lower edge with a turned-back portion and adapted for insertion within said pocket, said turned-back portion serving to accommodate the lower edge of a card, and a retainer cooperating with said supplemental holder and adapted to retain the latter and a card thereon to said main holder. 75

7. In a visible index card filing device, the combination of a main holder with means for retaining it within a filing drawer, said holder being provided at its lower edge with a pocket, a supplemental card holder provided at its lower edge with a transversely extending turned-back flap and adapted to be inserted within said pocket, and a retainer 80 adapted to overlap and detachably retain the upper part of said supplemental holder and the upper part of a card thereon, to said main holder. 85

8. In a visible index card filing device, the combination of a main holder with means for retaining it in a filing drawer so that it may be swung upwardly and rearwardly about a transverse axis adjacent its upper edge, said holder being provided in its lower edge with 90 a transversely elongated recess formed by a substantially U-shaped strip of transparent material attached to the lower edge of said main holder, a supplemental card holder adapted at its lower edge to be inserted within said transparent strip, and a retainer 95 cooperating with the upper edge of said supplemental holder adapted to overlap and retain the latter and a card thereon to said main holder. 100

9. In a card filing device, the combination of a main holder with means for retaining it in a filing drawer so that it may be swung upwardly and rearwardly about a transverse axis adjacent its upper edge, said main holder being provided in its lower edge with a transversely elongated recess, formed by a substantially U-shaped strip of transparent material secured to the lower edge of said main holder, a supplemental card holder provided at its lower edge with a turned-back portion and adapted to be inserted in said transparent strip, and a retainer applied to said main holder and adapted to overlap the upper edge 115 of said supplemental holder and the upper 120 edge of a card thereon. 125

In testimony whereof I affix my signature.
C. W. LAND.
